DESCRIPTION

U.S. PATENT DOCUMENTS

FIG. 1 is a perspective view of a booster seat showing my
new design;

D. 303,878	10/1989	Goldsmith	.....	D6/368
D. 355,986	3/1995	Myers	.....	D6/356
D. 366,965 *	2/1996	Meeker et al.	.....	D6/333
D. 417,964 *	12/1999	Kain	.....	D6/333
D. 419,786 *	2/2000	Kain	.....	D6/333
4,205,877 *	6/1980	Ettridge	.....	297/256.13
4,720,141	1/1988	Sakamoto et al.	.....	297/284
4,772,070	9/1988	Leto, Jr. et al.	.....	297/219
5,116,097	5/1992	Bulgari	.....	296/64
5,125,717	6/1992	Sköld et al.	.....	297/250
5,829,834	11/1998	Silverman	.....	297/250.1
5,833,314	11/1998	Mitschelen et al.	.....	297/237

FIG. 2 is a front elevation view thereof;
FIG. 3 is a back elevation view thereof;
FIG. 4 is a right-hand side elevation view thereof, the
elevation view of the left-hand side being a mirror image of
the right-hand side elevation view;
FIG. 5 is a top plan view thereof; and,
FIG. 6 is a bottom plan view thereof.
The mechanical features of the booster seat are shown in
broken lines for illustrative purposes only and do not form
a part of the present invention.
